(57) **CLAIM**

The ornamental design for a bottle-shaped spray container as shown and described.

DESCRIPTION

1. Bottle-shaped spray container

1.1 : Perspective

1.2 : Front

1.3 : Back

1.4 : Left

1.5 : Right

1.6 : Top

1.7 : Bottom

1.8 : Exploded

1.9 : Exploded

1.10 : Exploded

1.11 : Exploded

1.12 : Exploded

Bottle shaped container with spray dispenser.

1 Claim, 12 Drawing Sheets
